SNOWPLOW

Ira R. Wenner, Sycamore, Ohio

Application January 13, 1948, Serial No. 2,060

8 Claims. (Cl. 294—54)

1

This invention relates to snow plows, especially to a convertible snow plow that has a pusher plate associated therewith and adapted for manual propulsion when used as a snow pusher plate and adapted for attachment to mechanical means when used as a snow plow.

Heretofore there have been many different types of snow shovels and snow plows provided, but none of such structures known to me have been adapted for use both as a relatively small manually propelled snow pusher plate or shovel, and also for use as a relatively large snow plow which can be secured to and pushed by a lawn mower, tractor or the like. Obviously, the type of snow cleaning device required by any individual will vary widely at different times and with different amounts of snowfalls.

The general object of the present invention is to provide a new and improved snow plow that is characterized by its ready convertibility for use as a manually propelled snow shovel or pusher.

Another object of the invention is to provide a sturdy, low cost snow plow.

A further object of the invention is to provide a snow plow blade which has a curved lower section that is adapted to be sprung into engagement with a snow pusher plate.

Another object of the invention is to provide a snow plow that can be slid into engagement with a snow pusher plate, and be locked into engagement therewith in any desired manner.

A further object of the invention is to provide a snow plow which is adapted to permit snow to slide into engagement therewith upon initial movement of the snow plow.

Another object of the invention is to provide a snow plow with a relatively blunt lower edge to permit the plow to slide freely over a lawn, loose pebbles or the like, without engaging therewith.

The foregoing and other objects and advantages of the invention will be made apparent as the specification proceeds.

Attention is directed to the accompanying drawings, wherein:

Fig. 1 is a perspective view of a snow plow embodying the principles of the invention;

Fig. 2 is a side elevation of the snow plow of Fig. 1;

Figs. 3 and 4 are fragmentary vertical sections taken on lines 3—3 and 4—4 of Fig. 1;

Fig. 5 is a side elevation indicating one method of assembly of the snow plow of Fig. 1; and

Fig. 6 is a side elevation of the snow plow blade of the invention.

2

Referring now to the details of the structure shown in the accompanying drawings, a snow plow indicated generally by the numeral 10 is shown and it primarily comprises a pusher plate 11 and a plow blade 12. The pusher plate 11 is of generally rectangular shape and is curved inwardly from its lower to its upper edge. The pusher plate 11 is formed from any conventional material, such as steel and it has a handle 13 secured thereto by means of a backing sheet or mounting bracket 14 that is riveted or otherwise secured to the pusher plate. The handle 13 may be formed from any desired material and it may be provided with any conventional attachment means for securing it to a tractor or other prime mover, as hereinafter explained. For ordinary use of the pusher plate 11, as a snow shovel or pusher, the handle 13 provides a manual control element for this portion of the snow plow 10 which is adapted for use as a separate element.

As a salient feature of the present invention, the plow blade 12 is removably associated with the pusher plate 11 so that the blade may be removed and the pusher plate used by itself for snow moving functions. The plow blade 12 is provided with a rearwardly turned lower edge strip 15 that extends the length of the plow blade on its lower surface. The lower portion of the plow blade 12 is of curved shape, similar to the pusher plate 11, only of a smaller radius of curvature, as best indicated in Fig. 6, which shows the normal position of the plow blade when not subjected to external forces. The upper portion of the plow blade 12, as indicated at 16, is substantially flat with the upper edge of the plow blade being turned over at 17 to provide an edge reinforcing and gripping portion for the plow blade. To facilitate engagement of the plow blade 12 with pusher plate 11, a second engaging strip 18 is secured to the back surface of the plow blade 12. This engaging or mounting strip 18 is of generally inverted U-shape in section and it extends transversely of the plow 10 in parallel relationship with the edge strip 15, but spaced an appreciable distance therefrom whereby pusher plate 11 can be received between the two vertically spaced strips 15 and 18. Normally, the plow blade 12 is formed from sheet steel or other suitable material and has a slight resiliency in that it can be partially flattened out by tensional stress applied thereto in the direction of curvature of the plow blade.

Normally the plow blade 12 is assembled on the pusher plate 11 by engaging the edge strip 15 of the plow blade with the lower edge of the pusher

plate, then the plow blade may be placed on its face and the pusher plate 11 can be compressed down against the plow blade so as to flatten same out. At the same time, the edge strip 17 may be grasped and pulled outwardly of the plow to aid in flattening the plow blade 12 and in springing the engaging strip 18 over and into engagement with the upper edge portion of the pusher plate. The plow blade 12 is disassembled from the pusher plate by a reversal of the above process wherein the plow blade is again partially straightened out to snap the engaging strip 18 off of the edge of the pusher plate.

In some instances, it may be desirable to have a special reinforcement on the lower edge of the plow blade 12 and a separate reinforcing member 19 is shown associated therewith and secured thereto in any desired manner, as by spot welding.

Normally, the plow blade 12 is of different curvature than the pusher plate 11 in the associated portions thereof and this different curvature will aid in retaining the two members in engagement. It also is within the scope of the present invention to have the plow blade 12 formed of relatively heavy rigid sheet metal whereby in such instances the plow blade would be slid into engagement with the pusher plate 11 by relative lateral movement thereof. Any desired locking lugs or bars could be associated with the plow blade for preventing relative movement between it and the pusher plate after they are once assembled.

It will be understood that in talking about the use of the snow plow, it normally is adapted for being positioned at an angle of about 90° with relation to the direction of movement of the same so that the snow is gathered up before the plow and then pushed over to the side of the plow and out of engagement with the plow. Figs. 2 and 6 of the invention show that the lower edge portion of the snow plow of the invention when assembled has a very gradual inclination. This inclination preferably is about one inch vertically in the first three inches of length of the snow plow, which construction facilitates the starting movement of the snow plow when engaged in relatively deep snow.

Fig. 5 of the drawing, as stated hereinbefore, shows one method of springing the plow blade 12 into engagement with the pusher plate 11. In this instance, it is shown where the plow blade is primarily being lifted by hand so as to snap its upper engaging strip 18 over the top edge of the pusher plate 11. However, the engagement usually will be effected by placing the plow blade on its face and then flattening out same by engaging the lower edge of the pusher plate 11 therewith and springing the upper part of the plow blade to a flattened position, which action may be aided by tension exerted through the flanged upper edge 17 of the plow blade.

Fig. 5 shows that the plate 11 normally is of a greater radius of curvature than the blade 12 while Fig. 2 shows that the blade 12 may bend the plate 11 slightly inwardly by engaging therewith so that the assembly has a curvature intermediate that of the blade 12 or plate 11 alone.

While one complete embodiment of the invention has been disclosed herein, it will be appreciated that modification of this particular embodiment of the invention may be resorted to without departing from the scope of the invention as defined by the appended claims.

Having thus described by invention, what I claim is:

1. A snow plow comprising a concave snow pusher plate, a handle, a bracket securing said handle to the rear surface of said pusher plate, a plow blade of appreciably greater height and width than said pusher plate, said plow blade being provided with a concave lower section and a substantially planar upper portion, said plow blade being adapted to be flattened slightly by an external force for temporarily lengthening same slightly and having a rearwardly turned lower edge adapted to engage with the lower edge of said pusher plate, and an inverted substantially U-shaped engaging strip secured to the rear portion of said plow blade and extending transversely thereof at about the middle thereof, said engaging strip being adapted to be sprung into engagement with the top edge of said pusher plate by flattening same whereby said plow blade can be removably associated with said pusher plate.

2. A snow plow comprising a snow pusher plate which is curved in vertical section, a handle, a bracket securing said handle to the rear surface of said pusher plate, a plow blade of appreciably greater height and width than said pusher plate, said plow blade being provided with a concave lower section and a substantially planar upper portion which has a reinforcing edge thereon, said plow blade having a rearwardly turned lower edge adapted to engage with the lower edge of said pusher plate, and an inverted substantially U-shaped engaging strip secured to the rear portion of said plow blade and extending transversely thereof at about the middle thereof, said engaging strip being adapted to engage with the top edge of said pusher plate whereby said plow blade can be removably associated with said pusher plate.

3. A snow plow comprising a concave snow pusher plate, a handle secured to the rear surface of said pusher plate, a plow blade of appreciably greater height and width than said pusher plate, said plow blade being provided with a concave lower section, said plow blade having a rearwardly turned lower edge adapted to engage with the lower edge of said pusher plate, and an inverted substantially U-shaped engaging strip secured to the rear portion of said plow blade and extending transversely thereof at about the middle thereof, said engaging strip being adapted to engage with the top edge of said pusher plate when said plow blade is flattened to elongate same slightly.

4. A snow plow apparatus comprising a pusher plate having a handle secured thereto, a plow blade which is larger than said pusher plate and also slightly concave in vertical section, said plow blade having a rearwardly and upwardly bent lower edge, and inverted substantially U-shaped clamp means associated with said plow blade on the rear surface thereof for engaging with the upper edge of said pusher plate, said plow blade being adapted to be sprung into engagement with said pusher plate by engaging the lower edge of said snow plow and said clamp means therewith.

5. A snow plow apparatus comprising a pusher plate having a handle secured thereto, a plow blade which is slightly concave in vertical section in at least a portion of its vertical length, and substantially U-shaped strip means associated with vertically spaced parallel portions of said plow blade on the rear surface thereof, said strip means being positioned in opposed relation with the open ends thereof adjacent each other for engagement with opposed vertically spaced edges of said pusher plate.

6. A snow plow apparatus comprising a pusher

plate having a handle secured thereto, a plow blade which is slightly arcuate in vertical section, and substantially U-shaped strip means associated with spaced portions of said plow blade on the rear surface thereof for engaging with the edges of said pusher plate and removably securing said plow blade thereto.

7. A snow plow as in claim 4 wherein a reinforcing strip is secured to the outer surface of the lower edge of said plow blade to provide a blunt surface therefor. 10

8. A snow plow as in claim 6 wherein said plow blade has a very gradual upward curve in its first several inches of length.
